UNITED STATES PATENT OFFICE.

CHESTER WILLIAM LORENZ, OF MINNEAPOLIS, MINNESOTA.

TRUNK.

Application filed January 14, 1926, Serial No. 81,207.

My invention relates to trunks and an object is to provide a water-tight and dust-tight trunk particularly adapted for carrying on automobiles. My invention includes 5 special means for making water-tight and dust-tight, all of the joints between the body portion of the trunk and a cover hinged thereto so that the contents of the trunk will be fully protected while the trunk is being 10 carried.

The full objects and advantages of my invention will appear in connection with the detailed description thereof and the novel 15 features embodied in my inventive idea will be particularly pointed out in the claims.

In the accompanying drawings which illustrate a practical embodiment of my invention, Fig. 1 is a front elevational view 20 of the trunk. Fig. 2 is a side elevational view thereof. Fig. 3 is a view in section on the line 3—3 of Fig. 4. Fig. 4 is a view in section on the line 4—4 of Fig. 3. Fig. 5 is a view in section on the line 5—5 of Fig. 2. Fig. 6 is a fragmentary side elevational view 25 showing the cover lifted. Fig. 7 is a view in section on the line 7—7 of Fig. 1. Fig. 8 is a front view showing the cover lifted. Fig. 9 is a fragmentary view of the rear 30 portion of the cover. Fig. 10 is a view in section on the line 10—10 of Fig. 9. Fig. 11 is a detailed sectional view.

It will be understood that the trunk comprises a box-like structure having a hinged 35 cover. Referring to the construction shown in the drawings, the trunk is provided with a bottom 12, a front wall 14, a rear wall 16, two end walls 18 and 20, and a top member 22, the latter constituting a portion of the cover. As shown in Fig. 11, the walls may 40 be made of veneer consisting of the three layers *a*, *b* and *c*. As shown in Fig. 7, the front edge of the top member 22 is dovetailed into the upper edge of a horizontal wooden bar 24 whose outer surface is rounded 45 and a strip 26 disposed at right angles to the member 22 is dovetailed into the lower edge of the bar 24. The bar 24 and the strip 26 constitute part of the cover, the latter being completed by two end pieces 28 whose 50 lower edges are inclined as best shown in Fig. 2 so as to fit upon the inclined top edges of the end walls 18 and 20. When the cover is closed, the end pieces 28 fit outside of strips 30 secured to the inside of and projecting up above the end walls 18 and 20 while 55 the portion 26 of the cover fits outside of a

strip 32 secured to the inside of and projecting up above the front wall 14. The rear ends of the pieces 28 butt against the rear wall 16. In order to make a tight joint 60 therewith, the rear ends of the pieces 28 have thin plates 34 preferably of metal secured to the outside and these plates as shown in Fig. 4 project rearwardly in engagement with the ends of the wall 16. The 65 interior of the trunk is lined with waterproof fabric 36 which, as shown in Fig. 10, extends in one piece over the contacting mitered edges of the rear wall 16 and top member 22 of the cover so as to seal this joint. 70 The exterior of the trunk is covered with waterproof fabric 38 which as shown in Fig. 5 extends up over the exposed surface of the end strips 30 and as shown in Fig. 7 75 extends up over the exposed surface of the front strip 32. The fabric 38 also extends around the lower edges of the strip 26 and end pieces 28. At the top of the trunk, the fabric 38 extends over the contacting mitered 80 surfaces of the top member 22 and rear wall 16 and this portion of the fabric, as shown in Fig. 10, terminates at the bottom edge of a hinge. This hinge is secured over the fabric 38 and consists of an upper member 40 attached in suitable manner to the top member 22 and a lower member 42 attached in suitable manner to the rear wall 16. As shown in Figs. 5 and 7, the inside 85 of the cover is provided with packing material such as a strip of felt 44 which engages the top edge of the side strips 30 and the top edge of the front strip 32 when the cover is closed.

The advantages of my invention will now 90 be obvious. The trunk is covered on the outside and is lined on the inside with waterproofing material so that it can be readily washed. The construction of tight joints for all places where the cover engages the body portion of the trunk as previously described 95 in detail prevents the entrance of water and dust when the trunk is in use and makes it particularly adapted for carrying at the rear of an automobile where it is secured in any suitable or customary manner.

I claim—

1. A trunk comprising a box-like structure having a hinged cover provided with end pieces and thin plates secured to the rear ends of said pieces, said plates overlapping the rear wall of said structure for making a tight joint when said cover is closed.

2. A trunk comprising a body member, a cover for said body member, said cover including a top member hinged to said body member, a horizontal bar rounded on its outer surface and into the upper edge of which the front edge of said top member is set and a downwardly extending strip whose

upper edge is set into the lower edge of said bar, and a covering of water proof fabric extending over said top member, horizontal 10 bar, and downwardly extending strip.

In testimony whereof I hereunto affix my signature.

CHESTER WILLIAM LORENZ.
